UNITED STATES PATENT OFFICE

IVAN ORNBERG, OF DETROIT, MICHIGAN, ASSIGNOR TO HUPP MOTOR CAR CORPORATION, OF DETROIT, MICHIGAN, A CORPORATION OF VIRGINIA

RUNNING BOARD ASSEMBLY

Application filed May 21, 1928. Serial No. 279,486.

This invention relates to vehicles and more particularly to running board assemblies thereof.

One of the primary objects of the present invention is to provide a running board assembly which lends itself to economical manufacture and which may be easily and quickly assembled or disassembled.

Another object of the invention resides in the novel means employed for detachably securing the mat or covering to the running board and kick plate thereof.

A further object of the present invention is to provide a running board assembly wherein the kick plate and dust shield are secured to the running board by common detachable securing means.

Other objects and novel features of construction of this invention will be more fully hereinafter described.

In the accompanying drawings:

Figure 1 is a top plan view of a running board assembly embodying my invention.

Figure 2 is an edge elevation of the construction shown in Figure 1 and showing fragments of the front and rear fenders.

Figure 3 is a vertical sectional view taken on the line 3-3 of Figure 1.

Figure 4 is a vertical sectional view taken on the line 4-4 of Figure 1.

Figure 5 is a fragmentary vertical sectional view taken on the line 5-5 of Figure 1.

Figure 6 is a fragmentary sectional view taken on the line 6-6 of Figure 2.

Referring now to the drawings, 1 is a chassis sill member, 2 designates L-shaped running board supporting brackets bolted to and projecting laterally outwardly from said sill member 1, 3 is a running board mounted on the horizontal arms 4 of said brackets, and 5 is an apron or dust shield extending downwardly from the sill member 1 to the running board 3. As shown the running board 3 extends between the front and rear fenders 6 and 7 respectively and rests upon and is welded to lateral flanges 8 and 8' of suitable channel shaped supporting members 9 bolted to the horizontal arms 4 of the brackets 2. Preferably this

running board 3 is formed of sheet metal and is provided along its outer longitudinal edge with a depending flange or apron 10 that extends below and conceals the brackets 2 and supporting members 9.

The shield 5 overlaps the upper flange 11 of the sill member 1 and is provided at its lower longitudinal edge with an inturned lateral flange 12 that is secured by bolts 13 to the running board 3 at the inner longitudinal edge of the latter.

A mat 14 of suitable material such as rubber covers the running board 3 and depending flange 10 and is preferably detachably secured thereto. As shown, the mat is clamped at its inner edge between the running board 3 and the inturned flange 12 of the shield and is secured at its outer edge by a metal strip 15 to the depending flange 10 of the running board. This strip 15 is vulcanized to the mat 14 at the outer edge thereof and preferably is embedded therein and has a series of tongues 16 that are bent upwardly around and against the depending flange 10 of the running board. However, if desired, the strip 15 may have a continuous upturned portion instead of the spaced tongues 16, but in any event serves as a reinforcement for the outer edge of the mat and is designed to prevent scuffing the rubber from the board. Moreover, with this construction, the mat 14 is provided at its opposite ends with flanges or beads 17 and 18 that overlap the front and rear fenders 6 and 7 respectively, and thereby conceal the joints between said fenders and the running board.

With the present construction, two kick plates 20 and 21 respectively are detachably secured to the running board 3 and shield 5 and serve to protect the latter from being damaged by persons entering or leaving the vehicle body. As shown each kick plate consists of a steel plate 23 and a rubber mat 24 vulcanized thereto. The plates 23 have inturned flanges 25 extending between the running board mat 14 and the inturned flange 12 of the shield 5 and held in place by certain of the bolts 13, and are provided at their upper edges with lateral flanges 26.

that extend through openings 27 in the shield 5 and are secured by bolts 28 to in-turned flanges 29 of the shield 5. The plates 23 also have inturned lateral flanges 30, 31 and 32 respectively, that extend toward but are spaced slightly from the outer face of the shield 5 by overlapping lateral flanges or beads 33, 34 and 35 respectively of the rubber mats 24.

10 In the process of construction, the inner edge of the rubber mat 14 is bolted to the sheet metal running board 3 and the dust shield 5, after which the mat 14 is pulled over the running board and is clamped in place by the tongues 16 of the sheet metal strip at the outer edge of the mat.

Thus, from the foregoing description, it will be apparent that I have provided a very practical and efficient structure having parts that may be easily and quickly assembled or taken apart or replaced. Hence, my assembly is a decided improvement over the usual running board constructions in which the rubber mat is vulcanized to the board. Moreover, the arrangement of the rubber mat 14 with respect to the running board 3 of my assembly is such that the general practice of using metal molding or binding strips for the rubber mat at the edges of the running board has been eliminated entirely. It will also be noted that the bolts 13 serve as a common securing means for the running board 3, shield 5 and kick plates 20 and 21, and that the bolts 28 provide a very convenient means of attachment for the kick plates to the shield.

While it is believed that from the foregoing description, the nature and advantages of the invention will be readily apparent, I desire to have it understood that I do not limit myself to what is herein shown and described and that such changes may be resorted to when desired as fall 45 within the scope of what is claimed.

What I claim as my invention is:

1. In a running board assembly, the combination with a sill member, and a running board supporting bracket carried thereby, 50 of a running board mounted on said bracket, a running board dust shield carried by said sill member, a kick plate carried by said shield, and a common detachable connection between said shield, kick plate and running board.

2. In a running board assembly, the combination with a running board, of a running board shield and a kick plate having a portion clamped between portions of said running board and shield.

3. In a running board assembly, the combination with a running board and a shield, of a mat on said running board, and a kick plate having a portion clamped between portions of said mat and shield.

4. In a running board assembly, the combination with a running board, of a running board shield associated with said running board, a kick plate associated with both said running board and shield, and a detachable connection between said kick plate and shield including flanges projecting inwardly from said shield and kick plate, and a detachable connection between said flanges. 75

5. In an assembly of the class described, the combination with a running board shield, of a kick plate including a metal plate spaced from said shield but having inturned flanges bearing against said shield, and a covering of rubber for the sheet metal plate entirely concealing the same, including said inturned flanges. 80

6. In combination, a running board dust shield having an opening therein and an inturned flange at the edge of said opening, and a kick plate associated with said shield and having an inturned flange projecting through the opening aforesaid and secured to the inturned flange of said shield. 90

7. In a running board assembly, the combination with a running board, having a depending flange at the outer longitudinal edge thereof, of a running board mat on said running board, and a detachable connection between said mat and board including a metal strip having a portion permanently connected to said mat and having another portion return bent around said depending flange. 95

8. In a running board assembly, the combination with a running board provided along its outer longitudinal edge with a depending flange, of a running board mat mounted upon said board and having a depending portion overlapping said flange, and a metal strip vulcanized to said overlapping portion and having a portion extending around and upwardly upon the inner side of said depending flange. 100

9. In an assembly of the class described, the combination with a running board shield, of a kick plate having a body portion spaced outwardly from said shield and terminating at one edge in an inwardly projecting flange extending through an opening in said shield and secured to the latter. 110

10. In a running board assembly, the combination with a running board having a dust shield, of a kick plate for said dust shield, and a mat seated upon said running board and having a portion clamped between said kick plate and running board. 120

11. In a running board assembly, the combination with a running board, of a running board shield connected to said running board, a kick plate having a body portion spaced outwardly from said shield and terminating in inwardly extending flanges secured to said shield and a non-metallic cov- 125

ering for said kick plate having portions secured to said flanges.

12. In a running board assembly, the combination with a running board terminating at its outer edge in a depending flange, of a non-metallic mat mounted upon the running board and having a portion overlapping said depending flange, and a metallic strip embedded in the inner surface of the portion aforesaid of the mat and engaging the depending flange of the running board.

In testimony whereof I affix my signature.
IVAN ORNBERG.
